The invention disclosed herein is concerned with electromagnetic relays. The object of the invention is to provide a relay of simple construction, comprising simple parts, and thus being particularly adapted for automatic production.

This object is realized by the provision of a relay comprising a plate in which is inserted at least one core member of pin-like configuration, extending perpendicularly to the plane of the plate, such core member serving as an electrical conductor as well as a magnetic conductor, and an armature which is magnetizable and also serves as an electrical conductor, such armature cooperating with at least one core member to execute circuit switching relay functions.

The individual components required for the construction of the relay can be easily fabricated. The combination of the components as contemplated by the invention adapts the relay particularly to serve the intended purpose. The connection between the plate and at least one cover member can be particularly effected in the automatic fabrication, since the surface of the plate provides accurate reference areas for the proper disposition of the component parts. This is also true so far as the electrically conductive armature is concerned, the accurate position of which, with respect to the core member and the plate, can be definitely determined in automatic fabrication, thereby also determining the required contact spacing.

The armature is suitably constructed as a flat component which is in particularly advantageous manner arranged substantially in parallel with the plate, thereby obtaining a compact relay structure. The core member is in such a case advantageously inserted in the plate so that its end which faces the armature is substantially flush with the corresponding side of the plate or protruding only slightly therefrom, thus contributing further toward a compact structure of the relay.

While the plate may be made of insulating material, for example, ceramic material, it is particularly advantageous, especially so far as the fabrication of the relay is concerned, to employ a metallic plate. Such a plate is mechanically strong and adapted to be subjected to the relatively great stresses occurring in automatic fabrication, without affecting its dimensions, and permitting to define with greatest accuracy the reference areas which are available for the construction of the relay.

The core member may be secured in the plate by sealing means made of glass or materials having similar properties, advantageously employing for this purpose pressure fusing technique. The connection between the plate and the core means may thus be made gastight in simple manner, which is of advantage in the further construction of the relay, as will be presently explained more in detail. Securing of the core means in the plate in this manner has, in the case of a metal plate, the advantage of providing a satisfactory electrical insulation between the corresponding parts. The fused seals are very strong and withstand stresses that may occur incident to the automatic fabrication operations.

It may be mentioned at this point that it is known to secure cores of electromagnetic relays by fused glass seals formed under pressure. This technique has been applied

in a known arrangement employing bushings which are inserted cores. The bushings are components requiring for their production a more elaborate operation than is required for the plate employed in the present invention.

5 Moreover, the bushing does not provide the favorable reference areas for the construction of the relay. The known relay also requires elaborate contact means controlled by the armature, which call for a relatively large space.

10 The core or cores to be secured in the plate by glass seals are advantageously widened at the end thereof at which they are inserted in the plate. This simplifies the fabrication in which annular glass bodies are placed upon the cores and surrounding the latter within the range of 15 corresponding openings formed in the plate, the connection between the parts being thereupon secured by heating. The widening of the respective cores assures the glass parts in accurate position with respect thereto and prevents spreading of the glass in fluid condition to the free end of the core or to the surrounding area of the plate, thus avoiding contaminations which would have to be removed subsequently, since the free end of the core forms a contact in cooperation with the armature of the relay made according to the invention.

25 The requirement is being posed for some time, that the armature, especially when it is also utilized as an electrical conductor, should be disposed in a closed or sealed chamber. In a relay made according to the invention, such a chamber can be provided in simple manner by placing a cover upon the plate, such cover, in cooperation with the plate, defining the closed space or chamber for the armature. For example, the plate may be provided with upwardly drawn rim upon which is placed a plane plate. However, the plate is advantageously formed plane and the cover is provided with angularly bent rim and positioned upon the plate. The cover may be removably connected with the plate. It is, however, of advantage to provide for a fixed connection between the cover and the plate, which is produced in automatic fabrication without difficulties, for example, by welding or soldering a metallic cover to a metallic plate.

30 The cover is advantageously connected with the plate in hermetically tight manner, so that the armature can be arranged within a space or chamber which is evacuated or filled with a protective gas. Such a hermetically tight connection is easily effected by welding or soldering the parts together. The cover may be provided in known manner with suction stubs for effecting evacuation and subsequent filling of the enclosed space with protective gas, whereupon such stubs are sealed. It is understood, 35 of course, that the core or cores must be projected through the plate in gastight manner.

40 The cover may be provided with an annular flange-like rim for engagement with a marginal zone of the plate. Such construction of the cover is particularly suitable for welding or soldering the parts together since they are in engagement over relatively large portions thereof. Guide means or positioning means are advantageously provided on both parts to facilitate the automatic operation applied for effecting the connection therebetween, such guide means determining the mutual positions of the parts. Such guide means may be realized in simple manner by forming an annular depression along the marginal zone of the plate, and disposing in such depression the marginal portion of the cover, that is, the previously mentioned flange formed on the cover.

45 The end of the core which cooperates for contact making with the armature is advantageously formed spherically. The substantially flat armature will in this manner form a practically constant accurately define contact engagement with the core, regardless of the angular position

thereof with respect to the core, without having to resort to adjusting operations which increase the costs.

Upon the part of at least one core which projects from the side of the plate facing away from the armature, is provided at least one magnetizing winding. Such arrangement of the winding is easily effected in automatic operation.

In the event that a plurality of cores are inserted in the plate, such cores are magnetically connected by means of a yoke plate extending parallel therewith. This yoke plate may be provided with holes through which the cores project, requiring, of course, care to provide for electrical insulating the parts with respect to one another.

In a very simple embodiment, the relay may be constructed with only one core which is inserted in a metallic plate, the armature thereby effecting contact between the plate and the core. In a similarly simple embodiment, employing a metallic cover, the armature which extends between the cover and the single core, effects contact between the parts.

A relay constructed in the above described manner requires relatively very little space, since particular contact devices are eliminated. The construction of the relay with a hermetically tightly enclosed space or chamber for the armature results in the great advantage of requiring for the enclosed space only one single lead-through, namely, for the core, thus reducing to the lowest possible number the places at which leakage might occur.

The armature is advantageously journaled by means of a spring. In the last two described simple embodiments of the invention, an electrically conductive connection between the armature and the plate or cover, may be produced by such spring in simple manner by connecting the spring electrically conductively with the plate or the cover, for example, by welding the spring to the respective part.

In a structure having only one core inserted in the plate, the contacting between the plate and the core can also be effected by causing the armature, in its attracted position, to directly interconnect these parts by engagement therewith. An electrical connection between the armature and the plate may of course be additionally effected by the armature spring. For the direct connection between the plate and the cover, by the armature, the parts are advantageously mutually arranged so that the core area cooperating with the armature, lies flush with the surrounding plate surface. The advantages resulting therefrom reside not only in the contacting aspects, but also in the fabrication of the relay, that is, in this instance, in the connection between the plate and the core. In automatic operation, the desired position of the core in the plate may be readily obtained by the use of a planar backing member in alignment with the core and the plate.

The armature comprises two mutually independent parts lying alongside one another and fastened preferably to respective extensions of a spring, thus resulting in a dual contact and therewith in improved contacting operation. The cover is advantageously provided with an inwardly extending boss for engagement with the armature so as to determine the normal position thereof. The spring for holding the armature may be fastened to such a cover, for example, by welding.

A relay made according to the invention and equipped with such a cover offers particular advantages which adapt it for automatic fabrication. These advantages will now be briefly described.

The plate surface upon which is positioned the cover offers an accurate reference area. Assuming the armature spring to be welded to the cover, the armature will engage the previously mentioned boss which extends inwardly therefrom. The spring may be used in completely plane condition without any pretensioning thereof. There are accordingly two components, namely, the plate carrying the core which is inserted therein, such core lying for cooperation with the armature in a plane which is

disposed in an accurate relative position with respect to the plate surface, and the cover with the armature, and such components are to be connected with one another. Upon connecting these components with one another, the most important parameter of the relay, namely, the spacing between the core and the armature, which is equivalent to the contact spacing, depends solely on one single dimension, that is, the spacing between the plate and the cover part which extends parallel therewith. This dimension can be maintained with great accuracy, for example, upon forming the cover with angularly bent rim which lies in engagement with the plate. The spacing between the core and the armature will accordingly automatically result with the required great accuracy upon connecting the respective components with each other.

The boss which projects inwardly of the cover may be made in the form of an indentation, the depth of which can be accurately fixed according to a predetermined dimension.

However, the boss projecting inwardly of the cover may also be formed by an electrically conductive pin extending through the cover, resulting in the possibility of utilizing such pin, in cooperation with the armature, as a normal or break contact. It is likewise possible to make the pin of magnetically conductive material in combination with a cover made of non-magnetic material, for example, of brass. Such construction will offer the possibility of arranging for a normal contact, and will result in the further advantage of placing upon the pin at least one energizing winding for additionally controlling the operation of the armature.

Upon constructing the relay with only one core which is inserted in the plate, the condition, insofar as the flow of the flux is concerned, can be improved by arranging at least one flux conducting member extending in parallel with the part of the core on which is provided the energizing winding, and magnetically connecting such member with the core by a yoke plate extending parallel therewith. The flux conducting member and the yoke plate may be made of one piece, for example, in the form of a pot-like member which embraces the energizing winding.

As previously mentioned, there may be provided a yoke plate, extending in parallel to the core plate, and having holes or openings formed therein for cores which extend therethrough. The free ends of the cores are in such a case so arranged that they may be utilized as contact terminal pins. The relay may then be plugged, for example, into holes formed in a printed circuit plate so as to form connections with the circuitry, and the ends of these core-pin-terminals can be soldered to corresponding parts of the circuit, thereby fastening the relay in position on the plate of the printed circuit. The relay is very light in weight owing to the compact structure thereof, and such fastening will therefore fully suffice and obviate separate fastening means which normally would otherwise be required.

In the event that contact elements, serving only as electrical conductors and cooperating with the armature, are required in addition to the electrically and magnetically conductive core which is inserted in the plate and cooperate with the armature, such additional contact elements can be advantageously provided on the plate which carries the core. Such contact elements are advantageously inserted in the plate, extending in parallel with the core and being of the same length and configuration as the core.

A relay constructed in this manner therefore offers, insofar as automatic fabrication is concerned, all the advantages observed in connection with a relay having core means operating as electrical and also as magnetic conductors. In an automatic fabrication operation, the positions of the additional contact elements may be related to the reference areas of the plate surface with the same accuracy as that of the core, since these contact elements are inserted in the same plate as the core. The devices

required for the insertion or placement of the contact elements can therefore be constructed in a similar manner as the devices used for the insertion or placement of cores.

The relay conducted in accordance with the invention is particularly adapted for combination with a plurality of like relays to form a relay set. A relay set may thus be constructed upon a common plate, retaining thereby, insofar as the fabrication is concerned, all advantages offered by the individual relay. A relay set with very compact space saving structure may be provided in this manner.

Moreover, such a relay set may be built with parts arranged in various manner. Thus, the cores of the various relays can be placed or inserted in a plate with relatively large area, in desired distribution, for example, in a plurality of rows disposed one in back of the other. It is, however, also possible to construct the relay set in the manner of a known relay strip or bar, that is, with a plurality of relays disposed one alongside the other.

A further structural simplification of the relay set according to the invention may be achieved, in connection with relays having closed chambers for the respective armatures, formed by the covers in cooperation with the corresponding plates, by combining in a common component the covers of at least some of the relays.

Still another simplification is achieved by likewise combining in a common component at least some of the yoke plates, cooperatively associated with the respective relays, extending parallel with the corresponding core plates and magnetically connecting the cores.

Upon using relays with spring-journalled armatures, at least some of the relays may be journalled on a spring band or strip which is common thereto. For example, such a spring band may be provided with window-like cutouts formed therein, whereby the webs between the cutouts can be used for fastening the armatures, the latter lying within the window-like contacts of the spring strip.

Accordingly, the number of individual parts required for the construction of the relay set can be reduced to a far reaching extent, thereby resulting in simplification of the fabrication.

Further details and features of the invention will be brought out in the description which is rendered below with reference to the accompanying drawings, showing embodiments thereof.

FIG. 1 shows in cross-sectional representation a relay according to the invention, comprising a plate in which is positioned a core, and a cover disposed upon the plate and forming therewith a closed space for the armature, a boss being formed on the cover for engagement with the armature in the normal position thereof;

FIG. 2 is an elevational view of the inside of the cover and the armature means cooperating therewith;

FIG. 3 represents in cross-sectional view a relay similar to the one shown in FIG. 1, but having a pin projecting through the cover for engagement with the armature in the normal position thereof;

FIG. 4 illustrates in cross-sectional representation a relay provided with two cores;

FIG. 5 indicates in cross-sectional view a relay according to the invention comprising two magnetically and electrically conductive cores and a contact element which is only electrically conductive and cooperates with the armature;

FIG. 6 shows in cross-sectional representation a relay set or bar provided with relays constructed according to the invention, the arrangement being such that the armatures of the relays extend serially as viewed in longitudinal direction of the set;

FIG. 7 is a cross-sectional transverse view taken along lines I—I of FIG. 6; and

FIG. 8 represents an interior view of the cover employed in the relay set shown in FIGS. 6 and 7.

The arrangement shown in FIG. 1 comprises a metallic

plate 1 and a core 2, the latter being sealed gastight in position by a seal 3 of glass or similar material. The inner end 4 of the core 2, which is spherically formed, is flush with the inner plane of the plate 1. Numeral 10 indicates a cover having a flange 11 disposed in a marginal depression formed in the plate. The cooperation of these parts determines the accurate position of the cover on the plate. The cover is made of metal and is hermetically tightly welded to the plate.

Numeral 13 indicates the armature which is by means of a spring 12 journaled on the cover, inside thereof, the opposite ends of the spring 12 being welded to the cover and to the armature, respectively. The armature is in the normal position thereof in engagement with a boss 14, formed by indentation of the cover and inwardly projecting therefrom at an area aligned with the core 2.

Upon the outwardly extending portion of the core 2 is disposed the energizing winding or coil 6. Numeral 7 indicates a yoke plate having a hole formed therein through which the core projects as shown. A flux conducting member 8 extending in parallel with the core 2 is disposed between the yoke plate 7 and the core plate 1.

The armature 13 is attracted by the core responsive to energization of the winding 6, appropriate electrical circuit connections being of course provided in this as well as in all other embodiments, and the armature accordingly engages the spherically shaped end 4 of the core. Since the armature 13 is over the spring 12 electrically conductively connected with the metallic cover, there will be closed a circuit which is by suitable means connected respectively with the core and the plate or the cover. With appropriate construction of the relay, the armature will not only engage the core but also part of the surface 5 of the plate 1, thereby establishing a circuit extending over the spring and the armature between the plate and the core.

The area of the armature which establishes contact engagement with the core and also the corresponding area or point of the cover, may be coated with a contact material of noble metal, for example, silver. The same applies for the surface 5 of the plate and the surface of the armature cooperating therewith.

The free outer end of the core projects through a hole formed in an insulating plate 15 which carries a conductor 16 printed thereon. This conductor is soldered to the core, for example, by immersion soldering, thereby establishing an electrical connection between the conductor and the core, such connection also serving for fastening the relay in place on the insulating plate 15.

The armature is constructed of two independent parts, as shown in FIG. 2, which are soldered to extensions 17 and 18 of the armature journalling spring 12, the latter being welded to the cover as already described.

Parts in FIG. 3 which correspond to identical parts shown in FIG. 1, are identically referenced. The cover 35 is in FIG. 3 made of non-magnetic metal, through the wall of which extends in gastight manner a magnetically conductive pin 9, such pin being, for example, welded to the wall of the cover. The armature is in the normal position thereof, in engagement with the inner end of the pin 9. A coil or winding 20 is provided on the outwardly protruding part of the pin 9. Accordingly, the operation of the armature can be controlled by the action of the coil 20 additionally to the action of the coil 6.

The core 22 is at its upper end provided with an enlargement 19, such enlargement facilitating the fusing operation of the seal 3 and preventing the flow of the sealing material beyond the space extending between the core 22 and the plate 36.

The relay shown in FIG. 4 is provided with two cores 23 and 24, which are at 34 sealed gastight in position in the metallic plate 21. Journalled in the core 24, by means of a spring 25, is the armature 26 which also serves as electrical conductor. Upon the plate 21 is placed the cover 27, having a boss 28 formed therein, for example

by indentation thereof, the armature being in its normal position in engagement with this boss. The metallic core 27 is hermetically tightly welded to the plate 21. Upon the core 23 is provided an energizing winding 29. Numeral 30 indicates a yoke plate for magnetically interconnecting the cores 23 and 24. The cores extend through holes formed in the yoke plate, and the free ends of the cores are plugged into holes formed in the insulating plate 31 which is provided with printed conductors such as 32 and 33. The free outer ends of the cores are soldered to these conductors, thereby forming electrical connections and serving also for holding the relay in position on the printed circuit plate.

The example illustrated in FIG. 5 comprises a plate 35 carrying in addition to two cores 36 and 37, which serve as electrical and magnetic conductors, a member 38 which forms a solely electrically conductive contact element for cooperation with the armature 39. The armature 39 is slightly V-shaped and tiltably journaled upon the centrally disposed core 36 by means of a spring 40. Upon the centrally disposed core is provided the magnetizing winding or coil 41. The armature 39 is disposed in a closed chamber formed by the cover 42 in cooperation with the plate 35. The cores 36 and 37 are magnetically interconnected by a yoke plate 43.

In the normal position of the relay, the spring 40 holds the armature 39 in contact engagement with the core 37, thereby establishing connection between the cores 37 and 36. Upon energization of the magnetizing winding 41, the armature is tilted to its alternate position, breaking engagement with the core 37 and establishing a connection between the core 36 and the contact element 38.

FIGS. 6 to 8 show a relay set constructed of a plurality of relays made according to the invention. There is provided a metal plate 44 in which are positioned a plurality of cores extending perpendicularly to the plane of the plate 44. The cores are secured in position by fused glass seals 61. To each relay is assigned a core 45. Upon the plate 44 is disposed a cover 46 which is connected hermetically tight therewith. A spring strip or band is welded to the cover on the inside thereof, such spring strip carrying the relay armatures, the respective armatures being made of two parts 48 and 49 which are welded to extensions 50 and 51 of the spring strip. The corresponding welding spots are indicated at 52 and 53. The connecting points between the spring strip and the cover are indicated by numeral 54. The spring strip extensions 50, 51 project in the case of all relays, except the lowermost relay, into window-like cutouts 55 formed in the spring strip 47. The spring strip presses each armature against a boss 56 projecting inwardly from the cover 46 in alignment with the corresponding core.

The bosses 56 may be made in the form of indentations or maybe in the forms of pins extending through the cover.

Upon each core 45 is provided a magnetizing winding or coil 57. The cores are magnetically interconnected by means of a yoke plate 58 which is common to all relays of the set, the various cores projecting through holes in the yoke plate without establishing electrical connections therewith. Magnetically conductive members such as 62 are provided between the core plate 44 and the yoke plate 58, such members extending in parallel with the respective cores. The free outer ends of the cores are plugged into an insulating plate 59 which is provided with printed conductors 60 to which the cores can be connected by soldering.

Upon energization of a magnetizing winding, there will be produced a flux, such as is indicated by arrows in connection with one of the relays shown in FIG. 6. The corresponding armature is accordingly attracted and produces an electrical connection respectively between the involved core and the cover, and the plate by contact engagement of the armature with the core and plate, such connection extending over the restoring spring of the re-

5 spective armature. Therefore, a circuit is closed which extends over the plate and the respective core. A terminal connected to the plate is common to all relays of the relay set.

Upon using a plurality of cores for each individual relay, it will of course be possible to control with such relay completely separate circuits, whereby the core plate 44 does not serve as an electrical conductor.

It is of course understood that the circuitry required in all aspects of the relays may be provided in accordance with known and well understood teaching.

Changes may be made within the scope and spirit of the appended claims which define what is believed to be new and desired to have protected by Letters Patent.

We claim:

1. An electromagnetic relay, comprising a magnetizable electrically conductive core, a magnetizing winding carried by and electrically insulated from said core, a carrier for said core in the form of a plate having substantially rectangular cross section, said core being of pin-like configuration and inseparably secured in electrically insulated relation with respect to said carrier, said pin core extending perpendicularly to the plane of said carrier plate, a magnetizable armature, disposed at one side of said carrier, having a part disposed opposite said core and cooperable therewith to form operative contacts of the relay, the surface of the carrier at the armature side thereof forming a reference plane for the disposition of the armature, the core, engaging portions of the contacts, and associated relay parts, and the surface of the opposite side of the carrier forming a reference plane for the magnetizing winding, and means forming a flux return path between said core and carrier, the armature being disposed for direct opposition to the core contacted thereby and a part of the plate surface, to act as a part which carries the operatively effective magnetic flux.

2. An electromagnetic relay according to claim 1, wherein the carrier plate is formed of magnetizable metal, the core being hermetically inserted in sealing engagement with the aid of electrically insulating bodies of ceramic, the hermetically tight insertion being effected according to the pressure-glass-fusing technique.

3. An electromagnetic relay according to claim 2, wherein a cover is disposed upon the carrier plate, said cover cooperating with said plate to form a sealed space for the armature.

4. An electromagnetic relay according to claim 3, wherein the cover is at least partially made of metal and the armature effects in its working position contact between the cover and the operating core.

5. An electromagnetic relay according to claim 2, wherein there is only one core inserted in the carrier plate and the armature effects contact in its operating position, between the carrier plate and the core.

6. An electromagnetic relay according to claim 3, wherein the cover has an extension which projects into the closed space, the armature lying in its normal position against such extension.

7. An electromagnetic relay according to claim 6, wherein the extension is constructed as an electrically conductive pin which is inserted in the cover.

8. An electromagnetic relay according to claim 7, wherein the pin is made of magnetizable material and carries at least one winding.

9. A relay set comprising a plurality of electromagnetic relays according to claim 3, wherein the relay set has a common carrier plate taking the place of the carrier plates of the individual relays, in which common plate are inserted the cores of all relays, at least one flux-conducting piece being associated with each core and arranged parallel to the part of the associated core which carries the energizing winding, said flux-conducting piece being connected magnetically with such core by a yoke plate which extends parallel to the carrier plate, the cover

and yoke plate being respectively formed as a common cover and common yoke plate at least for a part of the relays of the relay set.

10. A relay set according to claim 9, wherein the armatures of at least part of the relays combined in the relay set, are journeled by way of a spring band which is common thereto.

11. A relay set according to claim 10, wherein the common spring band which carries the armatures, is provided with window-like cutouts formed therein, extensions for fastening the armatures being arranged on the webs of the spring band which separate the cutouts formed therein.

12. An electromagnetic relay according to claim 1, wherein the armature is formed of two mutually independent parts lying one next to the other, said parts being fastened to extensions of a spring.

13. An electromagnetic relay according to claim 1, wherein contact elements cooperating with the armature are inserted into the same carrier plate in which is inserted at least one magnetizable core which also serves as an electrical conductor, said contact element serving only as electrical conductors and being constructed in the same manner as the core and inserted in the plate.

14. An electromagnetic relay according to claim 1, wherein said means forming a flux return path comprises at least one flux-conducting piece arranged parallel to the part of the core which carries the energizing winding, said flux-conducting piece being connected magnetically with the core by a yoke plate which extends parallel to the carrier plate.

15. An electromagnetic relay according to claim 14, wherein the flux-conducting piece is formed as a core member which is inserted into the carrier plate, the armature of the relay being journaled upon such core member.

16. A relay set comprising a plurality of electromagnetic relays according to claim 1, wherein the relay set has a common carrier plate taking the place of the carrier plates of the individual relays, in which common plate are inserted the cores of all relays.
